UNITED STATES PATENT OFFICE.

HORATIO BARR, OF DETROIT, MICHIGAN.

FEEDING AIR TO FURNACES.

SPECIFICATION forming part of Letters Patent No. 390,198, dated October 2, 1888.

Application filed April 27, 1888. Serial No. 271,565. (No model.)

To all whom it may concern:

Be it known that I, HORATIO BARR, a citizen of the United States, residing at Detroit, county of Wayne, State of Michigan, have invented certain new and useful Improvements 5 in Feeding Air to Furnaces; and I declare the following to be a full, clear, and exact description of the invention, such as will enable others skilled in the art to which it appertains to 10 make and use the same, reference being had to the accompanying drawings, which form a part of this specification.

In the drawings, Figure 1 is a longitudinal central section of a boiler-furnace embodying 15 my invention. Fig. 2 is a plan view of the same. Fig. 3 is a section on the line *x x*; Fig. 4, a section on the line *y y*; Fig. 5, a section on the line *z z*.

My invention has for its object the production 20 of a furnace adapted for the burning of oil or other fuel. Great difficulty has been experienced in producing a furnace which would effect a perfect combustion of the fuel, and this has resulted in a considerable waste, 25 for the fuel unconsumed would fall to the bottom of the furnace and be burned upon its floor, thus not materially assisting the upper stratum of flame in communicating heat to the boiler. Moreover, that portion of the fuel in 30 a perfect state of combustion has not been confined to the whole length of the boiler-shell and its flues, but has been permitted to expend its heat upon that portion of the boiler immediately adjacent to the burner. These 35 difficulties I aim to overcome by my invention.

In carrying out my invention, A represents a boiler.

C is the furnace.

40 B represents passage-ways through which air is introduced to the furnace.

D represents dividing walls or partitions extending from the front end of the furnace back to its rear end, and at its rear end provided 45 with openings or perforations *d*, through which the air may enter between the said partitions, as indicated by the arrows.

E is a partition which serves to confine and form the top wall of the lower flues, B' B''. It 50 is sloped from its forward end upward toward the rear, beneath the rear end of the boiler, and in cross-section is made to conform some-

what to the curvature of the boiler-shell, so that its sides may serve to radiate the heat more directly against the boiler-shell. This 55 partition E at its forward end is terminated by an upright portion, E', then by a hinged portion, E'', and again by an upright section, E³, and finally terminates in an open flooring, E⁴. Beneath the portion E are arranged 60 bridge-walls *d'*, and beneath the portion E² of the partition is a high bridge-wall, *d''*.

The operation of this device will now be understood. The burner having been started, the draft of the chimney-flue draws air in 65 through the opening B. This air is deflected to the right and left and passed through the flues B', beneath the partition E E', &c., back to the rear end of the boiler, and on its way is considerably heated by the downward radiation of heat from above and from the side walls of the furnace. This air, passing to the rear end of the boiler, enters through the openings *d* into the middle flue, B³. Here it is by the bridge-walls *d'* deflected upward in close proximity to the lower surface of the partition E, and, passing thence forward, becomes quite highly heated. It is then obliged to pass over the high partition *d''*, and in thus doing passes in proximity to the most intensely-heated portion of the furnace. Here it is highly superheated. A portion of it continues on over the bridge-wall and is by the draft drawn up through the floor E and supplies the requisite amount at this point to produce combustion. This 85 air is, moreover, in so highly heated a condition that the fuel combines with it with avidity and the combustion is rendered complete. This combustion is, however, taking place upon the exterior surface of the particles of 90 oil and it takes an appreciable time for the whole substance of said particle to become consumed. It is in this ignited condition carried forward by the draft and meets with a fresh supply of this highly-heated air, which 95 escapes through the perforated section E' of the partition-wall. The combustion is therefore maintained until the combustible elements have been consumed, and none of it is permitted to settle upon the partition or adjacent parts of the furnace unconsumed for want of oxygen.

It is thus seen that not only is the air thoroughly and effectually heated before entering

the combustion-chamber, but is heated by the downward radiation from the intermediate partition, or, in other words, by the heat which would be otherwise wasted so far as concerns the serving of a useful purpose in raising steam. So, also, the fuel thrown into the furnace for consumption is held in close proximity to the boiler, where the burning mass is all caused to do effectual work in raising steam.

Again, the partition-walls gradually contract from the front toward the rear, so that the mass of fuel once ignited is not permitted to settle before it is wholly consumed; but this gradual contraction of the space from front to rear causes the draft to become stronger and stronger as the burning fuel advances, and so keeps it moving close to the boiler until it is in the boiler, or in its flues or tubes perfectly consumed and the whole of it utilized to the best advantage in the raising of steam.

This device is equally applicable with any of the various forms of burners, and for any of the various varieties of furnaces, and the combustion being maintained from the forward end to the rear end of the boiler with substantially uniform intensity the boiler-shell is not impaired as heretofore by the unequal expansion due to the greatly-increased heat its forward end has heretofore sustained, and to which its rear portions have not been subjected.

Of course I do not limit myself strictly to the particular formation of the partition-wall, whereby it is divided into the several parts E', E², E³, and E⁴; but this arrangement may be varied without departing from my invention, it being only essential that a suitable obstacle may be presented against which the ignited oil may impinge and be burst into flame, and the partition produced which will confine the burning mass close to the boiler, and from which the downward radiation may be utilized in heating incoming air.

What I claim is—

1. A boiler-furnace for steam-boilers, &c., the same consisting of a chamber beneath the boiler divided between its upper and lower portions by a partition, air-flues leading back beneath this partition and forward again be-

neath the same, and a perforated section through which said heated air is drawn by the draft into the combustion-chamber, substantially as described.

2. A boiler-furnace consisting of the combination, with a chamber beneath the boiler, of a partition dividing the said portion from the lower portion thereof, air-flues beneath the partition, through which air is drawn to the rear end of the furnace, thence forward again beneath the same, bridge-walls arranged to confine the air close to the surface of the said partition, and a perforated section, through which the air drawn by the draft is caused to enter the combustion-chamber, substantially as and for the purposes described.

3. A boiler-furnace consisting of a chamber beneath the boiler, having its upper portion divided from its lower portion by a partition, said partition inclined backward and upward from its end to the rear end of the boiler, air-flues beneath the partition, through which air entering at the forward end of the boiler is directed back beneath the partition to the rear end of the boiler, thence forward again beneath the same, bridge-walls for confining the air close to the surface of said partition, and one or more perforated sections, through which said air is drawn by the draft into the combustion-chamber, substantially as described.

4. A boiler-furnace consisting of a chamber below the boiler, the upper portion of which is divided from the lower portion by an intermediate partition, E' E² E³, said portions E' and E² being perforated for the passage of air, and in connection therewith air-flues extending from the front to the rear, thence forward again beneath said partition, and provided with deflecting bridge-walls, substantially as and for the purposes described.

In testimony whereof I sign this specification in the presence of two witnesses.

HORATIO BARR.
